POCKET CLINOMETER

Rollis A. Kennedy and Cecil A. Harms,
Seattle, Wash.

Application July 10, 1948, Serial No. 38,008

3 Claims. (Cl. 33—215)

1

Our present invention relates to the general art of clinometers, and more particularly to a small, compact clinometer that may most properly be termed a pocket clinometer.

Our present invention contemplates a compactly arranged clinometer of relatively small size so that it may be carried in the pocket of a workman much as he would carry a pocket cigarette lighter, and would be fully enclosed and protected during such periods. When the need arises for its use, the cover is opened and the clinometer may be used as it is by sighting along the sighting means or it may be placed upon a straight edge for a more accurate determination of slope extending over relatively short distances.

It is well understood that there has been a considerable development of devices intended to measure vertical angles; however, those observed have been of a bulky character and require special cases for carrying them and almost require the experience of a surveyor to make accurate determinations with them. Due to their structure, these instruments are expensive in first cost. In counter-distinction to this form of surveying instrument, we have produced a very compact unit that is intended for very economical manufacture and which, because of its slight bulk, can be carried generally by workmen who have need for the determination of angles in the vertical plane. Construction men have real need for such equipment as this, so that they make quick determinations of grades when they are operating earth-moving machinery particularly, so that they can get very close to the grades required without having surveyors in constant attendance. Transportation men have need for the determination of gradient very frequently, in the transportation of special contracting equipment, and the like, so that they may determine the methods that will have to be employed for moving that equipment. In actual construction work, there is further need for a device that will readily tell if a structural member is level or if it is at a definite batter or gradient, as required. It is to fulfill this need that we have produced our pocket clinometer.

The principal object, therefore, of our present invention is to provide a pocket clinometer that will be a compact, fully protected unit that will read vertical angles in gradient or degrees, or in any other unit that is desired.

A further object of our invention is to provide a pocket clinometer that admits of rugged construction, yet one which may be adjusted so that it can be expected to give very accurate readings. 55

2

A further object of our invention is to provide a pocket clinometer which employs gravity as the medium for moving the vertical angle indicating means, and to so mount this movable, gravity-controlled unit that it will be sensitive to small changes in vertical angles.

Further objects, advantages and capabilities will be apparent from the description and disclosure in the drawings, or may be comprehended or are inherent in the device.

In the drawings:

Fig. 1 is a perspective view showing our device with the cover open and ready for use.

Fig. 2 is a vertical sectional view taken in a plane normal to the axis of rotation of the gravity controlled unit.

Fig. 3 is a vertical transverse sectional view through our device.

Fig. 4 is a vertical sectional view taken longitudinally of our device, certain upper elements are partially broken away.

Fig. 5 is a diagrammatic view illustrating the manner of using our device.

Referring more particularly to the disclosure in the drawings, the numerals 10 and 11 designate respectively the upper and lower housing members of our device. These are hingedly secured together as by hinge 12, and are secured in their closed positions by the resilient latch 14, which engages a suitable protuberance on the housing member 10, as is designated at 15. This may be formed as part of the case, or might be a separate screw or member secured to the case. The lower housing member 10 is box-like in form and should conform generally to the proportions of a full-sized cigarette lighter, to the end that the device itself may be kept small and convenient to carry. The open top of housing member 10 is partially covered over by the top plate 17. This plate has a slot which should provide for the movement of the indicator dial and the indicator element itself.

Positioned near the top of housing member 10 and centrally therewith, are the aligned trunnion bushings 20 and 21; these bushings are preferably provided with exterior as well as interior threads so that they may be threaded into housing member 10 and come to a snug engagement with the housing due to the exterior flanges provided on ends of the bushings. This construction is probably best shown in Fig. 3. Adjustably positioned within bushings 20 and 21 are the trunnion screws 23 and 24, respectively. Each of the screws 23 and 24 are provided on their exterior ends with means for engagement with a screw

driver or wrench so that they may be adjusted easily for end-wise position. The inner ends of screws 23 and 24 are machined to provide the so-called frictionless bearings for the trunnion pin 26 of the gravity-controlled indicator 28. In order that the trunnion screws 23 and 24 may be locked in position once their adjusted position has been attained, we provide the lock nuts 30 and 31 which are adapted to be threaded upon the threaded screws 23 and 24.

The gravity-controlled indicator 28 consists essentially of a pointer 34 which is enlarged at its mid-point 36 to provide for the trunnion 26; the lower portion of indicator 28, as shown in Figs. 2 and 3, is provided with a relatively heavy weight 38. Attention is especially invited to this exact structure, as it embodies principles that are essential to the successful operation of our device—namely, that the trunnion 26 be of suitable design so that a very minimum of friction will occur at this point and secondly, that weight 38 has an over-abundance of mass so as to make our indicator sensitive to very small changes in angular displacement.

Coaxially disposed with respect to trunnion 26 is the graduated dial 40. Reference is made now to Fig. 2 in which it will be noted that the upper exposed segment of dial 40 has a mid-point zero, and is then graduated each side of zero in gradience, such as one on four, one on two, one on one, two on one, etc.

On the lower or buried portion of dial 40 it will be noted that the segment is graduated in degrees from a central zero each way. These two graduations have been found most generally useful. However, it will be readily apparent, it is believed, that any suitable form of graduations may be so employed and particularly is it desirable to have two different forms of stating the same general relationship, after the showing made in Fig. 2. When so arranged, the user of the equipment need not be constantly making conversions from one form of terminology to another; this is particularly true in so many forms of construction work where engineering data is supplied in certain terms, yet the workman in the field must use the terms in which their tools are graduated, and with which they are most familiar.

In keeping with our general plan of producing a simple, durable, sturdy device, we find it very desirable to have the slot through which dial 40 and pointer 34 extend as close-fitting as working tolerances will permit, and in order that there be no undue difficulties in manufacture, it is desirable to have a removable plate so that hub 42 may be inserted through the slot 43 formed within plate 17. We have combined with this requirement a friction-locking device so that the graduated dial 40 may be accurately zeroed or, if desired, may be given an artificial zero. This often occurs when an operation such as, for instance, a ship building ways, is all in a sloping plane, yet references want to be made from the normal to that sloping plane. We achieve this desirable capacity with our device by providing that hub 42 of dial 40 be a running fit on the unthreaded portion of the outside of trunnion bushing 21, so that the dial is free to revolve in any desired position. Then a V-shaped friction groove 46 is cut in the outer surface of hub 42, and adapted to form a locking engagement with this groove is an arcuate friction member 43. Friction member 43 is, in turn, fixedly secured to plate 50. It will be understood, it is believed, that by releas-

ing screws 52 and 53, the dial 40 will be unlocked and may be moved about its center of rotation and then re-locked in a new position. Plate 50 also serves to cover a cut-away portion of plate 17 so that, in assembly, hub 42 can be passed through the space thus provided. After the graduated dial and indicator 28 are in place, the trunnion bushings are then screwed into place, followed by the proper adjustment of trunnion screws 23 and 24, and finally the indicator is secured in adjusted position by means of lock nuts 30 and 31.

In using our pocket clinometer for normal usage, we prefer that the proper dial segment is accurately centered. This is achieved by loosening lock member 48 and placing the clinometer on the base that is adjustable and then, by reversal of the clinometers, possibly more than once, the zero point will be accurately determined. Lock member 48 is then secured fixedly in position by means of screws 52 and 53.

The usual manner of use will be to apply one of the plane surfaces of case 10 to a structural member or to a straight-edge for temporary use. The clinometer may be hand-held and aligned by sighting along one of its edges or by use of the fixed sights as 56 and 57.

It is believed that it will be clearly apparent from the above description and the disclosure in the drawings that the invention comprehends a novel construction of a pocket clinometer.

Having thus disclosed the invention, we claim:

1. In a pocket clinometer, of the type having an upper housing member and a lower housing member hingedly secured together; a latch adapted to hold said upper housing member in closed engagement with said lower housing member; a top plate for said lower housing member having a slot extending lengthwise thereof; trunnion bushings secured in axial alignment near the upper margin of said lower housing member; trunnion screws adapted to be adjustably positioned within said trunnion bushings; means for locking said trunnion screws in adjusted position; a trunnion pin axially disposed with respect to said trunnion screws and to be rotatably supported between the same; an indicator fixedly secured to said trunnion pin and adapted to revolve therewith; an upwardly extending indicator pointer and a downwardly extending weight-supporting arm formed as part of said indicator; an indicator weight secured to said weight-supporting arm; and a graduated circular dial, the improvement, comprising: a hub extending outwardly from said dial, adapted for rotary positioning upon one of said trunnion bushings; an annular V friction groove formed on the surface of said dial hub; a friction member mounted on said top plate with a flange extending downward through said slot, the lower friction edge of said flange being concave and fitting into said V friction groove, releasing screws running through said friction member into said top plate providing means whereby the graduated dial may be rotated and fixed in a desired position.

2. In a pocket clinometer, of the type having an upper housing member; a lower housing member; a latch adapted to hold said upper housing member in closed engagement with said lower housing member; a top plate for said lower housing member having a slot extending lengthwise thereof; trunnion bushings secured in axial alignment near the upper margin of said lower housing member; trunnion screws adapted to be

adjustably positioned within said trunnion bushings; a trunnion pin axially disposed with respect to said trunnion screws and to be rotatably supported between the same; an indicator fixedly secured to said trunnion pin and adapted to revolve therewith; an upwardly extending indicator pointer and a downwardly extending weight-supporting arm formed as part of said indicator; an indicator weight secured to said weight-supporting arm; and a graduated circular dial, the improvement, comprising: a hub extending outwardly from said dial, adapted for rotary positioning upon one of said trunnion bushings; a friction surface formed on said dial hub; a friction member adapted to engage said friction surface; means for adjustably positioning said friction member; and said graduated dial having one-half of its circumference marked in degrees and one-half marked in terms of the ratio between rise and distance for various angles.

3. In a pocket clinometer of the type having an upper housing member and a lower housing member hingedly secured together; a latch adapted to hold said upper housing member in closed engagement with said lower housing member; a top plate for said lower housing member having a slot extending lengthwise thereof; trunnion bushings secured in axial alignment near the upper margin of said lower housing member; trunnion screws adapted to be adjustably positioned within said trunnion bushings; means for locking said trunnion screws in adjusted position; a trunnion pin axially disposed with respect to said trunnion screws and to be rotatably supported between the same; an indicator fixedly secured to said trunnion pin and adapted to revolve therewith; an upwardly extending indicator pointer and a downwardly extending weight-
